UNITED STATES PATENT OFFICE.

DAMON BALE, OF LOUISVILLE, KENTUCKY, ASSIGNOR TO STANDARD SANITARY MANUFACTURING CO., OF LOUISVILLE, KENTUCKY, A CORPORATION OF NEW JERSEY.

DESIGN FOR A PIPE-BRACKET FOR WASH-SINKS.

52,623.

Specification for Design.

Patented Nov. 12, 1918.

Application filed August 3, 1917. Serial No. 184,353. Term of patent 14 years.

To all whom it may concern:

Be it known that I, DAMON BALE, a citizen of the United States, residing at Louisville, in the county of Jefferson and State of Kentucky, have invented a new, original, and ornamental Design for a Pipe-Bracket for Wash-Sinks, of which the following is a specification, reference being had to the accompanying drawing, forming a part hereof.

In the drawing, Figure 1, is a front elevation; Fig. 2, a side elevation; and Fig. 3, a central vertical section of my new design.

My design consists in the general outline and contour of the bracket, which comprises a rectangular base surmounted by a back the edges of which, skirted by flanges, converge to a bearing, and a shell-like projection which forms a receptacle.

Having thus described my invention, I claim:—

The ornamental design for a pipe bracket for wash sinks, as shown and described.

DAMON BALE.
